SAILBOAT HULL

Paul F. Humpley, 1218 Wilcox, Joliet, Ill. 60435

Continuation-in-part of abandoned design application Ser. No. 407,229, Oct. 17, 1973. This application Oct. 3, 1975, Ser. No. 619,520

Term of patent 14 years

Int. Cl. D12—06

U.S. Cl. D12—64

*Fig. 4.**Fig. 3.*FIG. 1 is a side elevational view of a sailboat hull embodying the ornamental design of this invention;

FIG. 2 is a top plan view thereof showing the integral merging of cabin, deck and bowsprit;

FIG. 3 is a front end view thereof; and

FIG. 4 is a rear end view thereof.

This application is a continuation-in-part of my prior pending design application, Ser. No. 407,229, filed Oct. 17, 1973, now abandoned.

I claim:

The ornamental design for a sailboat hull, as shown.
